UNITED STATES PATENT OFFICE

165,717

CHAIR

Fred C. Maurer, East Palestine, Ohio, assignor to
The Kenmar Manufacturing Company, East
Palestine, Ohio, a corporation of Ohio

Application October 24, 1950, Serial No. 12,706

Term of patent 14 years

(Cl. D15—11)

To all whom it may concern:

Be it known that I, Fred C. Maurer, a citizen of the United States, residing at East Palestine, in the county of Columbiana and State of Ohio, have invented a new, original, and ornamental Design for a Chair, of which the following is a specification, reference being had to the accompanying drawing, forming a part thereof.

Figure 1 is a perspective view of a chair with the footrest portion in lowered position, showing my new design.

Figure 2 is a perspective view thereof with the footrest portion in elevated position;

Figure 3 is a front elevation thereof; and

Figure 4 is a back elevation thereof.

The other side of the chair is a substantial duplicate of the side shown in Figures 1 and 2.

I claim:

The ornamental design for a chair, as shown.
FRED C. MAURER.
